(57) **CLAIM**

The ornamental design for a stringed instrument work station, as shown and described.

DESCRIPTION

FIG. 1 is a perspective view of a stringed instrument work station illustrating my new design;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines, where present, in all of the figures illustrate portions of the a stringed instrument work station that represent the environment of the claimed design and form no part of the claimed design.
